NEW YORK.

LOOSE-LEAF BINDER.

Application filed October 23, 1923. Serial No. 670,297.

Our invention relates to loose leaf post binders and more particularly to binders having flexible post members. This application is in part a continuation of our application Serial No. 596,344, filed October 23, 1922.

One object of our invention is to provide an improved, compact and simple form of binder and one whose mechanism can be operated quickly and easily. Another object of our invention is to provide an expandible ledger binder which opens like a book with a flexible back.

In the drawings—

Fig. 1 is a side elevation of the head of a binder embodying our invention, the dotted lines showing the clamping bars separated for the changing of the sheets;

Fig. 2 is a perspective view of the same part of the binder with the clamping bars separated and one cover turned back;

Fig. 3 is a transverse section on line 3—3 of Fig. 1;

Fig. 4 is a section of the clamping bar on line 4—4 of Fig. 3;

Fig. 5 is an elevation of the end member as seen from the left detached and as if looking to the right from line 4—4 Fig. 3;

Fig. 6 is a partial section of the upper clamping bar taken on the line 6—6 of Fig. 4;

Fig. 7 is a perspective view, disassembled, of part of the winding means;

Fig. 8 is a plan view of the top clamping bar partially broken away to show our four post form of construction;

Fig. 9 is an elevation of the two clamping bars showing our four post form of construction.

Our invention relates to the type of loose leaf binder in which the sheets are threaded on flexible posts or binding members and held between hollow clamping bars or tubes, into or through which pass the surplus lengths of the binding members. We have discovered a very simple, practical and compact construction of mechanism for operating the binder, which can be placed inside one of the clamping tubes and at the same time we have produced a backless construction which will open like a flexible-back bound book and lie flat on its back without rolling when the binder is open. It has been customary to make these ledger binders

with a fixed curved back which permits the binder to roll from side to side when lying open on its back. This manifest disadvantage to anyone wishing to make entries in the book, has also been overcome by our invention.

In our binder, hollow clamping bars 1, 2 are each hinged at each end to a cover 3 by a pin 4 inserted through a hole 9 in an end plug and hinge member 5 and into a cover loop 6 on the end of the cover (Figs. 2 and 6). The end plug and hinge members 5 are fastened on the ends of the clamping bars by screws 7 passing through holes 8 in the member 5. In the upper clamping bar these screws thread into independent disks 24^a closing the ends of the tube, while in the lower clamping bar, they each hold one end of a tie-rod 8^a lying lengthwise in the bar.

The clamping bars are connected by a collapsible brace which prevents them from moving lengthwise or twisting with respect to each other. By twisting or angular displacement we mean angular displacement of the clamping members with respect to each other whereby the longitudinal axes of the clamping members will form an angle with each other. We have shown this brace as consisting of two pairs of toggle levers 10, 11, each pivoted at one end to a lug 12 inserted in the clamping bars, while the other ends of each pair are joined together at pivot points 13 guided in slots 14 in a bar 15 running parallel to and between the clamping bars. These pairs of toggle levers 10, 11 preferably face in opposite directions, while each lever 10, 11 has pivotally connected to it a radius link 16 pivoted in turn to the bar 15 and forming a diamond with the pair of toggle levers and the other associated radius link. The lugs 12 pass through slots 17 in the clamping bars and are pivoted to rods 18 lying longitudinally inside them (see Figs. 1 and 6). The slots 17 are deep enough to permit these lugs to turn on the rods 18 in either direction and in consequence the two clamping bars can be turned slightly on their longitudinal axes with relation to each other as far as the slots 17 will permit (see Figs. 1 and 6). The clamping bars are shown turned on their longitudinal axes in one direction from parallel in Fig. 2. It will be understood, of

course, that the rocking connection between the brace and the clamping bars can be eliminated by simply making the lugs 12 rigid on the rods 18.

- 5 In place of every two posts on which the sheets are ordinarily threaded, we employ one continuous flexible binding member 19, preferably in the form of a cord. This cord can run from the lower clamping bar to the 10 upper one near one end, thence through the upper clamping tube to a position near the other end and back to the lower clamping tube. A bevelled bearing ring 30 can be used at each point where the flexible member 15 passes through the upper clamping bar. The ends can be secured to the lower clamping bar either directly or indirectly. We have shown each end of the cord 19 set in a ring 20 and fixed by a pin 21 extending 20 from each side of the ring, the latter holding the end of the cord in the lower clamping bar by bearing against the inside of the clamping bar frame 22 (see Fig. 1). Fas- 25 tened longitudinally in the upper clamping bar 1 in the independent disks 24^a is a winding shaft 23 squared at one end to receive a suitable winding key. Keyed to the center of this shaft is a winding disk 24 (see Fig. 7). There is a hole through the disk 30 near its circumference and the middle of the continuous cord or binding member 19 passes through this hole. It will be ap- 35 parent that revolution of the winding shaft will wind up the binding member helically on the shaft on each side of the disk 24 and thereby draw the clamping bars together. (See Fig. 3.) With this arrangement of the binding member and winding means any endwise pressures from the helices are di- 40 rectly opposed to each other and will neutralize each other entirely. We prefer to make the opening in the winding disk large enough to permit the binding member to pass freely through the disk. The tensions 45 of the two halves of the binding member are thus automatically kept equal by this slip of the binding member through the winding disk, without in any way disturbing the portions of the binding member passing through the sheets.

To prevent the binding member being unwound except when it is desired to change the sheets in the binder, we provide a ratchet mechanism (shown in Fig. 4) at 50 one end of the upper clamping bar. On the winding shaft 23 is keyed a ratchet wheel 25 normally engaged by a pawl 26 pressed on the wheel by a spring 27. When the binding member is wound on the wind- 55 ing shaft till the clamping bars grip the sheets, this ratchet and pawl will normally hold the winding shaft from turning and releasing the clamping bars.

To release the winding shaft and open the 60 clamping mechanism, we provide a cam 28

on a locking pin 29 set in the end plug and hinge member fitting over the ratchet and pawl. This end plug and hinge member is shown in Fig. 5. When the locking pin 29 is turned from the position shown in Figs. 1, 4 and 5 to the position shown in Fig. 2, the cam 28 pushes the pawl 26 clear of the ratchet wheel 25, and it is then only necessary to pull the clamping bars apart to be able to change the sheets in the binder. 70 There is a pin 30 projecting from one side of the locking pin 29 midway of its ends, which limits the rotation of the locking pin to the positions shown in Figs. 1 and 2 by coming in contact with the walls of the end 75 plug and hinge member.

The outer end of the locking pin 29 is slotted (see Figs. 1 and 2) to receive the edge of a coin or the handle of the key for the winding shaft to turn the locking pin. 80 The disk and the end plug bear indicating marks which show whether the mechanism is locked or open. Furthermore in our construction the brace and the friction in the winding means prevent full opening of the 85 clamping members and unintentional release of the sheets when the mechanism is unlocked. The clamping bars must be pulled apart—they will not fall on their backs and unwind the binding member of 90 their own accord because of the restricted size of the slots 17 and the friction in the winding mechanism. We have found that this winding mechanism permits rapid opening and closing of the clamping bars and 95 we have also found that the tensional elasticity of the cord 19 provides excellent co-operating tension with the ratchet and pawl, thus obviating the necessity for a spring. 100

Our construction is so compact and 105 adaptable that it can be used in large ledger binders requiring four or more posts as well as binders having only two posts. This construction is shown in Figs. 8 and 9 and differs from the construction shown in 110 the first seven figures only in that there are two disks 24 and two flexible members 19, on each shaft instead of one. The mechanism is so simple and compact that the 115 posts can be placed as close together as is required in any loose leaf post binder now 120 on the market. It will be apparent that the cords can be of round, flat or any desired cross section and that posts in any multiple of two can be furnished by duplicating disks 125 and cords. It should be further pointed out that if an odd number of posts is desired, one flexible member 19 can be cut off at the disk and only one half used.

The clamping bars are preferably made 125 with an enlarged portion adapted to lie just beyond the edges of the sheets and partially opposite them. This enlarged portion is preferably rounded so that when the binder lies open on its back and resting on these 130

enlarged portions the bars can be easily turned on their longitudinal axes. By putting the winding shaft in this enlarged portion of the upper bar and making the other 5 of the same size the bars afford a symmetrical basis for the binder when lying on its back and at the same time do not increase the total thickness of the binder unnecessarily. When there are so few sheets in the 10 binder that the bars have been drawn together till their enlarged portions touch each other the bars will tip so that the edges of the tubes furthest from the enlarged portions will always maintain a grip on the 15 sheets. The collapsible brace is connected to the clamping tubes at points close to the edges of the sheets by the parts already described, so that the slightest relaxing of the tension of the binding member will permit 20 the clamping bars to turn on their longitudinal axes and force the binding member to arch upward between them like the back of a flexibly bound book. It will be noted that the turning of the clamping bars on 25 their longitudinal axes also releases the sheets from all clamping pressure. If the binding member is fastened to the edges of the sheets rather than at a little distance from the edges it is not necessary to loosen 30 the binding member at all to enable it to arch up. We believe that this is the first binder with a rigid connection between the clamping bars which opens like a flexible-back bound book i. e. arches up the sheets 35 and releases them from clamping pressure. It will be evident that this construction is a great improvement over prior binders and especially over prior ledger binders.

What we claim is:—

40 1. In a loose leaf post binder, a pair of hollow clamping bars, and a longitudinal shaft in the upper of said bars, in combination with a binding member passing through said upper bar and having its ends fastened 45 to the lower of said bars, and a single winding means connected to the central part of said shaft adapted to wind said binding member on said shaft in two helices.

50 2. In a loose leaf post binder, a pair of hollow clamping bars, and a longitudinal shaft in the upper of said bars, in combination with a binding member passing through said upper bar and having its ends fastened to the lower bar, and a single winding means 55 connected to the central part of said shaft, through which said binding member slips freely, adapted to wind said member on said shaft helically.

60 3. In a loose leaf post binder, a pair of hollow clamping bars, a longitudinal shaft in the upper of said bars, a binding member passing through said upper bar and having its ends fastened to the lower bar, and a single winding means connected to the central part of said shaft, through which said 65

binding member slips freely, adapted to wind said member on said shaft helically, in combination with expansible bracing means directly fastened to said clamping members preventing angular displacement 70 of said clamping members with respect to each other.

4. A loose leaf post binder having a pair of clamping members and a flexible binding member adapted to cause said pair of clamping members to exert pressure on the sheets in the binder, in combination with means connecting said clamping members together in such manner as to prevent angular displacement thereof with respect to each other 75 and adapted to permit said clamping members to turn on their longitudinal axes to shift their pressure to the rear edges of the sheets, thus permitting the sheets to arch 80 upward. 85

5. A loose leaf post binder having a flexible binding member and a pair of clamping members, in combination with expansible bracing means connecting said clamping members and adapted to permit said clamping members to pivot on longitudinal axes 90 near the edge of the binding side of the sheets in the binder. 95

6. A backless loose leaf post binder having a flexible binding member and a pair of clamping members, in combination with expansible bracing means swivelly connected to each of said clamping members and adapted to permit said clamping members limited rotation on their longitudinal axes. 100

7. A backless loose leaf binder having a flexible binding member and a pair of hollow clamping bars each having a rounded portion lying beyond the edge of the sheets in the binder, said rounded portions at all 105 times forming a steady base for the binder when laid on its back in combination with expansible bracing means connecting said clamping bars and adapted to permit them to turn on their longitudinal axes in either 110 direction from normal. 115

8. A loose leaf post binder having a flexible binding member and a pair of hollow clamping bars each having an enlarged portion adapted to overhang the edges of the 120 sheets in the binder, in combination with expansible bracing means connecting said clamping bars and adapted to permit them to turn on their longitudinal axes and grip the sheets in the binder when the enlarged portions of the clamping bars are in contact with each other. 125

9. In a loose leaf binder, a pair of hollow clamping bars each having an enlarged portion lying beyond the edge of the sheets in the binder and partially on a line with the sheets, and a longitudinal shaft in the overhanging portion of the upper bar, in combination with a binding member passing through said upper bar and having its ends 130

fastened to the lower bar, and winding means connected to the central part of said shaft, through which said binding member slips freely, adapted to wind said binding member on said shaft in two helices.

10. In a loose leaf binder, hollow clamping bars, independent closure means fixed in the ends of said bars, and a longitudinal winding shaft revolvably mounted in said closure means in the upper bar, in combination with a disk keyed to the middle of said winding shaft, and a binding member having its ends fastened to the lower bar and passing freely through the upper bar and said disk, the latter being adapted to wind said binding member on said shaft in two helices, and expansible bracing means connecting said clamping bars and adapted to permit said clamping members limited rotation on their longitudinal axes.

11. In a loose leaf binder, hollow clamping bars each having an enlarged and round-

ed portion lying beyond the edge of the sheets in the binder and partially in line with the sheets, said portions at all times 25 forming a steady base for the binder when laid on its back, and a longitudinal shaft mounted directly in the overhanging portion of the upper bar, in combination with a binding member having its ends fastened to 30 the lower bar and passing freely through the upper bar, and a disk on said longitudinal shaft through which said binding member also passes freely, said disk being adapted to wind said binding member on 35 said shaft in two helices, and expansible bracing means connecting said clamping bars and adapted to permit said clamping members limited rotation on their longitudinal axes.

40 In testimony whereof we have signed our names to this specification,

ALWIN VON AUW.
CHAS. A. FINLEY.
